UNITED STATES PATENT OFFICE.

WALTER COVENTRY, OF PENDLETON, SALFORD, ENGLAND.

BURNER FOR INCANDESCENT GAS-LIGHTING.

1,070,875.

Specification of Letters Patent.

Patented Aug. 19, 1913.

Application filed November 29, 1912. Serial No. 734,162.

To all whom it may concern:

Be it known that I, WALTER COVENTRY, a British subject, residing at Pendleton, Salford, county of Lancaster, England, have invented certain new and useful Improvements in Burners for Incandescent Gas-Lighting, of which the following is a specification.

This invention relates to annular burners for incandescent gas lighting having perforations or outlets for the gas on the underside and a gas inlet chamber above the outlet perforations to which an inverted mantle is applied. I find in these annular burners for incandescent gas lighting, when made of large diameter and with a single gas inlet chamber, that it is not practicable with gas at a low pressure to draw in sufficient air, or to obtain an even distribution of the mixture of gas and air over all the gas outlet perforations at a pressure high enough to incandesce the mantle equally at all points.

The invention consists of an annular burner constructed with or divided by partitions into two or more chambers and fitted with a corresponding number of gas and air inlet pipes, one inlet pipe to each chamber of the burner.

Referring to the drawings Figure 1. is a sectional elevation. Fig. 2. is a sectional plan on line $x-x$ Fig. 1, showing a burner with two compartments. Fig. 3. is a sectional plan, showing three compartments. Fig. 4. is a plan of the underside showing the nipples, nozzles or perforations of the burner.

The burner A is constructed of annular shape to receive an annular inverted mantle A', and is provided with outlet perfora-

tions or nozzles B. The air and gas chamber I divide into compartments a' , a^2 , Fig. 2, or a' , a^2 , a^3 , Fig. 3, by partitions a which may be cast with the body of the burner or may be fitted into it and secured in any suitable way.

To each compartment or chamber a separate inlet pipe b' , b^2 , Fig. 2, or b' , b^2 , b^3 , Fig. 3, is attached so that the gaseous mixture is supplied to the several compartments independently of one another although at the same pressure. This gives a very even distribution of the gaseous mixture to all the nozzles B of the burner and consequently an even incandescence of the mantle at all points. The inlet pipes may be placed equidistant around the burner, as shown, and they may be regulated in any suitable manner.

This construction of burner enables only a part or section of the mantle of the burner to be ignited at one time so that one or more sections of the burner can be employed according to the intensity of the light required.

What I claim as my invention and desire to protect by Letters Patent is:—

An inverted annular burner for incandescent gas lighting provided with a plurality of compartments for the gaseous mixture, with a separate inlet pipe fitted to each compartment, and with a plurality of outlet perforations, substantially as described.

In testimony whereof I have hereunto set my hand in presence of two subscribing witnesses.

WALTER COVENTRY.
